UNITED STATES PATENT OFFICE.

NORRIS ELMORE CLARK, OF PLAINVILLE, CONNECTICUT, ASSIGNOR TO ROBERT S. ALLYN, TRUSTEE, OF NEW YORK, N. Y.

EXPANDED-METAL MACHINE.

1,314,504.

Specification of Letters Patent. Patented Sept. 2, 1919.

Original application filed February 15, 1915, Serial No. 8,354. Divided and this application filed March 7, 1917. Serial No. 153,151.

To all whom it may concern:

Be it known that I, NORRIS ELMORE CLARK, a citizen of the United States of America, residing at Plainville, Connecticut, have invented a new and useful Expanded-Metal Machine, of which the following is a specification.

The present invention relates to a machine for carrying out part of the method of my Patent #1,224,104 of April 24, 1917, and for making a product such as illustrated in my Patent #1,128,659, and this application is a division from Patent #1,224,104.

Briefly considered, the invention contemplates means for forming unslotted strips into ribs and at the same time opening the slotted portions of the stock in the oppositely inclined mesh work section having what has become known as "reverse-lay" of strands.

The stock is preferably slotted as illustrated in my Patent #979,130, but it will be understood that I consider other arrangements of slitting may be employed, for instance, as shown in my Patent #1,086,027.

Figure 1 is an end view showing the slotted stock and mechanism for bending or folding the unslotted portions, and opening the mesh work with the strands on opposite sides of the center of each slotted section inclined edgewise in opposite directions. The mechanism and stock are shown in full lines in the position before operation, and in dotted lines in the position in which the ribs are partially formed and the stock is partially open.

Fig. 2 is a similar view showing the parts in position with the ribs completely formed and the mesh work spread into a common plane.

The stock may be first slotted, for instance, by means of cutters as shown in my Patent #1,146,554. This forms slotted sections 5-5 leaving broad unslotted strips 6-6 connected by narrow bendable strands 7-7 and with intermediate central strips 8.

Jaws such as 10-10 are hinged or pivoted together at 11 to vertically movable slides 12. These jaws and slides are nor-

mally held pressed upward by springs 13 60 and the jaws normally lie open as shown in Fig. 1 supported above the cam faces 14-14. Each pair of jaws is shaped on its interior to correspond with the desired external shape of the rib to be formed at 6, and 55 above each pair of jaws is located a vertically movable punch member 15 preferably having the shape of the interior of the rib to be formed. Midway between the deep rib punches 15 is a relatively movable punch 60 16 adapted to engage the center of the slotted section. This punch is preferably grooved on its lower face and pressed downward by a spring 17. Below the punch 16 is preferably located a die 18 shaped at its 65 upper end so as to co-act with the groove in the lower end of the punch 16 to longitudinally corrugate or bend the strip 8 to form a rib 8'.

In operation, a slotted sheet is inserted 70 between the upper and lower dies, and the upper dies are moved downwardly. The dies 15-15 engage the centers of the broad unslotted strips and force them into the corresponding pairs of folding jaws. The 75 edges of the jaws support the edges of the unslotted strips as the centers of the strips are moved downwardly. The continued downward movement of the dies 15-15 forces the jaw carriers downward and thus 80 causes the jaws to be folded toward each other. This rib forming action folds the edges of the unslotted strips upward toward the sides of the dies 15-15, thus opening the slotted stock into mesh work between the 85 dies. The folding carries the edges of the unslotted strips upwardly out of their original plane relative to the central strips 8 and brings the edges of the ribs and the strands on edge relative to the original plane of the 90 stock, the inclination of the edges of the ribs corresponding to the inclination of the strands attached thereto. The opposite sides of each rib are inclined in opposite directions, and similarly the strands between adjacent ribs are inclined edgewise in opposite directions on opposite sides of the center of the mesh work section. This relative angular

relation permits the bending action of the ribs and strands to take place with a minimum application of force and a minimum strain in the fabric.

- 5 The central punch member or die 16 holds downward the center of the slotted section and thus facilitates the uniform turning of the strands on edge in opposite directions on opposite sides thereof. By shaping the dies 16 and 18 as shown, it is possible to fold or groove the strips 8 as shown in Fig. 2 at 8'. This draws the sides of the central unslotted strip so that they are substantially parallel with the edgewise inclination of the strands 15 attached thereto. In this way the strands are allowed to bend in a natural manner without being strained. The central strips 8 of the expanded sections may be carried into the same plane with the edges of the 20 deep ribs 6 by a proper proportional movement of the deep rib dies and the central engaging dies. This is facilitated by having the dies 16 spring-pressed and it may be desirable also to move the dies 18 upwardly. 25 Although the hinged jaws 10 are shown below the members 15, it will be obvious that the construction might be used with the parts inverted.

When the stock is slotted along diagonal 30 lines as shown in my Patent #979,130, it is desirable to move the center of each slotted section longitudinally relative to the margins. This may be accomplished by moving the dies 16 and 18 longitudinally 35 in the manner described for moving the die members 55 in my Patent #1,104,477.

From the foregoing it will be obvious that the deep ribs may be given any desired cross 40 sectional shape by suitably forming the jaws 10 and punches 15.

What I claim is:—

1. In an expanded metal machine, a plurality of pairs of exterior hinged rib forming members, sliding supports therefor, interior rib forming members movable to operate with said hinged members to move the same, cams for engaging said exterior forming members to cause them to fold together to bend the ribs, and intermediate 45 holding members between adjacent pairs of the exterior hinged rib forming members.

2. In an expanded metal machine, means for engaging the centers of relatively broad unslotted strips of a partially slotted sheet, 55 means for engaging the edges of said strips, one of said means being movable perpendicular to the plane of the stock and relative to the other means, means for carrying said edge-engaging means toward each other upon the interposed center-engaging means for folding the strips into deep ribs and means for holding the center of a slotted section as the edges of the strips are moved out of the plane of said center,

3. In an expanded metal machine, a plurality of pairs of exterior hinged rib forming members, sliding supports therefor, interior rib forming members movable to operate with said hinged members to move the same, means for folding said exterior hinged rib forming members, and intermediate holding members between adjacent pairs of the exterior hinged rib forming members. 65

4. In an expanded metal machine, vertically movable members, folding members carried thereby, cam abutments for said folding members and constituting therewith exterior rib forming means, interior rib forming means, one of said rib forming means being movable relatively to the other, said folding members coacting with said abutments as the interior rib forming means 70 coat with said folding members to fold the ribs and open the slotted section of a partially slotted sheet, and means for holding the slotted stock at opposite sides of the rib forming means. 80

5. In a machine for expanding partially slotted sheets, means for holding the centers 90 of slotted sections, means for folding unslotted strips to form ribs and thereby draw the edges of the slotted sections out of the plane of the centers of the slotted sections and open the slotted sections into mesh-work 95 having oppositely disposed lay of strands on opposite sides of the centers.

6. In an expanded metal machine, means for supporting the edges of relatively broad unslotted strips of a partially slotted sheet, 100 means for moving the center of the slotted section out of the plane of said edges and means for folding said edges out of the plane of said center and then back again into said plane to form ribs and open the 105 slotted section.

7. In an expanded metal machine, supports for the centers of slotted sections, means for holding the centers of unslotted portions and simultaneously carrying the 110 edges of the unslotted portions out of the plane of the centers of the slotted sections to form ribs and for subsequently bringing the centers of the slotted sections and the bases of the folded ribs into the same plane. 115

8. In an expanded metal machine, pairs of stationary cam-faces, plungers mounted to move between the cam faces of each pair, folding exterior rib forming members pivoted on a common center and mounted to 120 move between said cam faces and interior rib forming members adapted to coact with said folding members.

9. In an expanded metal machine, a pair of spring supported exterior rib forming 125 jaws pivoted on a common center and a vertically movable interior rib forming punch mounted to coöperate with each pair of

jaws and to force them toward each other as the punch descends between them to form ribs.

10. In an expanded metal machine, a series of pairs of inclined exterior rib forming jaws pivoted at their lower edges on a

common center and having gripping faces movable downward and toward each other and interior punch members adapted to force rib stock down between the jaws of 10 each pair simultaneously to form ribs.

NORRIS ELMORE CLARK.
